SANDING ATTACHMENT FOR BRICK MAKING MACHINES

Hugh L. Campbell, Hazleton, Pa.

Application June 9, 1936, Serial No. 84,383

2 Claims. (Cl. 25—115)

This invention relates to an attachment for brick making machines, and more particularly the invention resides in the provision of a sanding device which may be attached to any stiff-mud brick making machine for the purpose of applying sand to a column of brick clay prepared previously to the application of the sand thereto and from which bricks are to be formed.

The invention together with its objects and advantages will be best understood from a study of the following description taken in connection with the accompanying drawings wherein:—

Figure 1 is a side elevational view of the sanding attachment with parts broken away and shown in section.

Figure 2 is an end elevational view of the attachment.

Figure 3 is a bottom plan view of the attachment.

Figure 4 is an enlarged fragmentary view of the attachment taken at right angles to Figure 1 and with certain parts broken away and shown in section.

In accordance with the present invention the sanding attachment comprises a hopper or receptacle 5 for the sand. The bottom of the hopper or receptacle 5 comprises a block 6 of wood or other suitable material, and the walls of the hopper 5 at said bottom are provided with apertured flanges 7 through the medium of which and fastening elements 8 the bottom 6 is secured to the hopper.

Bolted or otherwise secured to the underside or face of the bottom 6 of the hopper is a plate 9 preferably of metal which supports the hopper on top of the strip of clay for reciprocation thereon.

There is also provided a pair of side strips 10 and each of these strips is provided at its respective opposite ends with bolts 11 the head ends 40 of which work in slots 12 provided therefor in the plate 9, and the heads of which are accommodated in suitable grooves 13 provided therefor in the underside of the bottom 6 and opening at the respective opposite side edges of said bottom 45 strip as will be clear from a study of Figures 1 and 4. It will thus be seen that the guide strips 10 are suspended from the plate 9 for lateral movement inwardly toward one another or outwardly away from one another.

50 The side strips 10 are normally urged toward one another through the medium of oppositely disposed springs 14. In this connection it will be noted that each of the strips 10 is provided at its respective opposite end with vertical bars 15 secured at their lower ends to the end edges of

the strips 10 as at 16. The springs 14 connect the bars 15 in pairs, each spring being connected at its respective opposite end with the bars 15 as at 16.

Also each pair of bars 15 is pivotally connected at its upper end with a cross-strip 17. Thus it will be seen that the springs 14 act on the bars 15 of each pair to urge the bars inwardly toward one another and consequently the strips 10 inwardly against the sides of the mud column 18 as 10 said column, on the usual conveyor 19 is caused to pass between the side strips 10 and under the hopper 5.

Adjacent one end thereof the bottom 6 of the hopper is provided with a transverse series of 15 spaced slots 20 that register with slots 21 provided therefore in the plate 9.

Slightly in advance of the slots 20 bottom 6 adjacent opposite side edges thereof is provided with additional slots 22 that align with grooves 23 20 provided on the inner faces of the strips 10 and which grooves as shown in Figure 4 taper downwardly and also progressively decrease in depth downwardly, with the groove slots 23 opening at the inner sides of the strips 10 so that the sand 25 passing into the grooves 23 through the slots 22 from the hopper 5 will be applied to the sides of the mud column 18.

In this connection it will also be appreciated that the sand discharging from the hopper 5 30 through the slots 20, 21 will pass onto the top face or surface of the column 18.

Obviously the sand fed to the top and sides of the column 18 will be rubbed into the column incidental to the reciprocatory action of the 35 sanding unit which action is imparted to the unit as the mud column 18 on the conveyor 19 passes between the side strips 10 and beneath the bottom 6.

For reciprocating the sand unit there is provided a suitably driven shaft 24 supported in suitable bearings 25 and equipped with eccentrics 26.

Each eccentric 26 has suitably engaged therewith an eccentric strap 27 to which is suitably 45 connected one end of a pitman arm 28, the opposite end of which arm is pivoted to one side of the bottom 6 of the hopper as at 29. Thus it will be seen that drive will be transmitted from the shaft 24 to the sanding unit for reciprocating the 50 unit as the sand is being applied to the top and sides of the column 18, and as said column is being conveyed through the machine. In this connection it will also be understood that the reciprocatory action of the bottom 6 and the side 55

members 10 will serve to work the sand thoroughly into the top and side faces respectively of the column 18.

It is thought that the utility and advantages of an invention of this character will be had without a more detailed description.

Having thus described the invention what is claimed as new is:—

1. In an apparatus for sanding a strip of clay, 10 the combination with a conveyor for moving the strip longitudinally, of a reciprocally mounted hopper disposed over said conveyor and having a bottom and a metallic smoothing plate below said bottom, said bottom and plate being so spaced 15 above the conveyor as to enable the plate to engage the top of said strip, a pair of side members swingably mounted on said hopper to depend from opposite sides of said plate, respectively, for relative lateral movement to engage the sides of 20 said strip, means for urging said members into engagement with the sides of the strip to smooth and shape the same, said plate and members being slotted to distribute sand on the top and sides of said strip, respectively, and means for 25 reciprocating said hopper longitudinally of said strip.

2. In an apparatus for sanding a strip of clay, the combination with a conveyor for moving the strip longitudinally, of a reciprocally mounted hopper disposed over said conveyor and having a bottom and a metallic smoothing plate below said bottom, said bottom and plate being so spaced 5 above the conveyor as to enable the plate to engage the top of said strip, pairs of links depending from opposite ends of said hopper, respectively, a pair of side members swingably supported by 10 said pairs of links beneath opposite sides of said plate, respectively, for relative lateral movement to engage the sides of said strip, means engaged with said links for urging said members into engagement with the sides of the strip to shape 15 and smooth the same, cooperating devices on the side members and plate for guiding lateral movement of the side members, means for reciprocating said hopper longitudinally of said strip, and 20 said bottom, plate and side members being slotted to distribute sand on the top and sides of said strip respectively.

HUGH L. CAMPBELL. 25
